DENCE, RHODE ISLAND.

DESIGN FOR A HANDLE FOR SPOONS, FORKS, OR SIMILAR ARTICLES.

SPECIFICATION forming part of Design No. 35,982, dated July 29, 1902.

Application filed November 22, 1901. Serial No. 83,347. Term of patent 7 years.

To all whom it may concern:

Be it known that I, THEODORE BENDER, a citizen of the United States, residing at Providence, in the county of Providence and State 5 of Rhode Island, have invented and produced a new, original, and ornamental Design for a Handle for Spoons, Forks, or Similar Articles, of which the following is a specification, reference being had to the accompanying drawings, forming part thereof.

Figure 1 is a front view, and Fig. 2 is a rear view, of the handle, showing my design.

The design consists in the conventional fiddle-shaped outline of the handle and the ornamentation, as shown in the drawings. The marginal edges of the sides of the handle are ornamented with raised beads foliated at the end attached to the article. At the junction of the blade with the stem and at the upper 15 end of the handle a fillet extends along the inner side of the marginal beads between the foliations. On the front of the handle a convex raised fillet extends along the center of

the stem, terminating in a scrolled foliation extending over part of the convex panel of 25 the blade of the handle. A scrolled cactus-leaf forms the crest at the upper end of the front of the handle. On the rear of the handle the central convex panel extends continuously over the blade and the stem. The 30 upper end of the rear is ornamented by a scrolled honeysuckle ornament.

Having thus described my invention, what I claim as new, and desire to secure by Letters Patent, is—

The ornamental design for the handle of a spoon, fork, or similar article, as herein shown and described.

In testimony whereof I have signed my name to this specification in the presence of 40 two subscribing witnesses.

THEODORE BENDER.
